(57) **CLAIM**

I claim the ornamental design for a holster assembly, substantially as shown and described.

DESCRIPTION

FIG. 1 is a perspective view of an embodiment of the holster assembly of the present invention wherein the clip is positioned within the slot of the holder;

FIG. 2 is a perspective view of an embodiment of the holster assembly of the present invention wherein the clip is removed from the slot of the holder;

FIG. 3 is another perspective view of the holster assembly of FIG. 1;

FIG. 4 is another perspective view of the holster assembly of FIG. 2;

FIG. 5 is a rear elevation view of FIG. 1;

FIG. 6 is a first side elevation view of FIG. 1;

FIG. 7 is a front elevation view of FIG. 1;

FIG. 8 is a second side elevation view of FIG. 1;

FIG. 9 is a bottom view of FIG. 1;

FIG. 10 is a top plan view of FIG. 1;

FIG. 11 is a perspective view of an embodiment of the clip of the holster assembly of the present invention;

FIG. 12 is another perspective view of the clip of FIG. 11;

FIG. 13 is a first side elevation view of the clip of FIG. 11;

FIG. 14 is a front elevation view of the clip of FIG. 11;

FIG. 15 is a second side elevation view of the clip of FIG. 11;

FIG. 16 is a bottom view of the clip of FIG. 11;

FIG. 17 is a rear elevation view of the clip of FIG. 11;

FIG. 18 is a top plan view of the clip of FIG. 11;

FIG. 19 is a first side elevation view of an embodiment of the holder of the holster assembly of the present invention;

FIG. 20 is a front elevation view of the holder of FIG. 19;

FIG. 21 is a second side elevation view of the holder of FIG. 19; and,

FIG. 22 is a rear elevation view of the holder of FIG. 19.

Dotted lines form no part of the claimed invention.
